COMBINED BOWL AND COVER

Johannes Brahm, Los Angeles, Calif.

Application July 27, 1951, Serial No. 16,054

Term of patent 14 years

(Cl. D44—10)

To all whom it may concern:

Be it known that I, Johannes Brahm, a citizen of the United States of America, residing in the city of Los Angeles, in the county of Los Angeles, State of California, have invented a new, original, and ornamental Design for a Combined Bowl and Cover, of which the following is a specification, reference being had to the accompanying drawing, forming a part thereof.

Fig. 1 is a perspective view of a combined bowl and cover, showing my new design;

Fig. 2 is a perspective view taken from the other side showing the cover partially removed;

Fig. 3 is a top plan view;

Fig. 4 is a rear elevational view; and

Fig. 5 is a front elevational view of the same.

I claim:

The ornamental design for a combined bowl and cover, substantially as shown.

JOHANNES BRAHM.
